UNITED STATES PATENT OFFICE.

THOMAS C. OCTIGAN AND WILLIAM PEACOCK, OF CHICAGO, ILLINOIS.

HORSESHOE.

SPECIFICATION forming part of Letters Patent No. 687,435, dated November 26, 1901.

Application filed February 21, 1901. Serial No. 48,268. (No model.)

To all whom it may concern:

Be it known that we, THOMAS C. OCTIGAN and WILLIAM PEACOCK, of the city of Chicago, in the county of Cook and State of Illinois, have invented certain new and useful Improvements in Horseshoes; and we do hereby declare that the following is a full, clear, and exact description thereof, reference being had to the accompanying drawings, and to the letters of reference marked thereon, which form a part of this specification.

This invention relates to improvements in horseshoes; and the invention consists in the matters hereinafter set forth, and more particularly pointed out in the appended claims.

In the drawings, Figure 1 is a top plan view of a horseshoe containing our improvements. Fig. 2 is a bottom plan view thereof. Fig. 3 is a transverse sectional view on line 3 3 of Fig. 2. Fig. 4 is a view of a fragmentary section on line 4 4 of Fig. 2. Fig. 5 is a central longitudinal section of the shoe shown in Fig. 2. Fig. 6 is a view of one of the rear ends of the body of the shoe.

As shown in said drawings, A designates the curved body of the shoe, which is provided on its lower surface with two continuous downwardly-extending flanges or calks A' A², forming between the same a channel A³, extending around the shoe on the under surface thereof. One or both of said calks may be longitudinally corrugated, and, as herein shown, the outer calk A' is so formed. The corrugated form of flange or calk A' greatly increases its bearing-surface, and therefore its adhesive force, upon the roadway. The inner calk or flange A² is made tapered, as shown in Figs. 3 and 5. Outside the outer flange or calk in the body of the shoe are located nail-holes a, through which the nails for attaching the shoe to the hoof of the horse are passed. Within said channel is seated a narrow rubber pad B, which entirely fills the channel and projects a slight distance beyond the margins of the flanges or calks A' A² to form part of the tread-surface. The ends of the rubber pad at the heel of the shoe are joined by an integral transversely-arranged rubber bar B', which is made of considerable width from front to rear of the shoe to insure a firm hold of the shoe on the roadway to prevent slipping. Said bar is curved between

its ends toward the toe of the shoe and has the general form of an arch in plan view. The purpose of so forming the connecting-bar B' is to permit the shoe to be made narrower or wider, as circumstances may require, when the shoe is being fitted to the horse's foot, it being the intention that said shoe shall be fitted when cold. By reason of the forward curvature of the central part of the connecting-bar said bar will be bent inwardly and assume a greater curvature when the heel of the shoe is made narrower, and vice versa. The bottom surface of the pad comprising the parts B B' is roughened, as indicated in Fig. 2, so as to insure the pad taking firm hold upon the roadway. Said connecting-bar is made of greater depth than the depth of the shoe at the toe thereof, the difference in depth being approximately one-quarter of an inch, whereby the upper surface of the shoe is forwardly inclined.

The body of the shoe A is provided on its upper surface with a rabbet a', which is filled with a body of rubber B², which is flush with the upper surface of the shoe radially outside of said rabbet. Said body of rubber B² is joined integrally with the pad, consisting of the parts B B', by means of integral connecting-bonds b, extending through openings a² in the body of the shoe, from the upper to the lower side thereof, as clearly shown in Figs. 3 to 6, inclusive. The rubber is applied to the several parts of the shoe and molded thereupon in any suitable manner to the shape shown, said rubber filling the channel A³ and rabbet a' and passing through the connecting openings a² from one side of the body of the shoe to the other to connect the rubber on both sides of the shoe. The rubber is thereafter subjected to a vulcanizing process to suitably toughen the same.

The rear ends of the body of the shoe are provided with offset parts A⁵ A⁵, which are embedded in the body of the rubber constituting the connecting-bar B'. Said offset parts or projections taper gradually from the upper surface of the body of the shoe, as shown in Fig. 4, to give the required strength at this part. Said extensions are located slightly below the level of the body of the shoe, and at the junction of the same with the body of the shoe, within the rear ends of the

groove A³, are formed oblique offset surfaces or shoulders a³, as shown in said Fig. 4. Such oblique offset surfaces tend to prevent the rubber pad from slipping backwardly in the 5 groove A³. The corrugation of the rim A' also aids to prevent longitudinal displacement of the part of the pad occupying the groove A³. Furthermore, it will be observed that the rear ends of the extensions A⁵ converge from their points of connection with the 10 body of the shoe and are closer at their rear than at their front ends. Said extensions being embedded in the rubber of the connecting-bar serve to prevent said bar from shifting rearwardly, and thereby also aid to hold 15 the pad as a whole in place on the shoe.

As before stated, the connecting-bar B' is made deeper than the shoe in advance of the same, and the projections A⁵ of the body of 20 the shoe, at the heel thereof, are offset above the tread-surface of the flanges or calks A' A³, so that below said projections is provided a large body of rubber, which receives through 25 said offset parts the weight brought upon the heel of the shoe. The heel or tender part of the foot rests upon the yielding connecting-bar B' and the rear quarters of the hoof of the foot rest on the rear ends of the unyielding metal body of the shoe. When the weight 30 of the horse is brought upon the shoe, the part of the connecting-bar below the offset parts A⁵ is compressed until the tread of the calks in front of the connecting-bar comes in contact with the ground. As the rear 35 quarters of the hoof rest upon the unyielding rear ends of the body of the shoe the weight of the horse is transmitted therethrough to the roadway, and as the connecting-bar is depressed with the rear end of the body of the 40 shoe upon the compression of the lower part of said bar in the manner described it will be seen that undue pressure is avoided on the heel of the horse.

It will be understood that the weight of the 45 animal when brought upon the shoe is transmitted to the roadway through the calks of the shoe, the pad B, occupying the groove between the calks, yielding until contact of the calks with the roadway is effected. The purpose 50 of the pad B is to prevent the animal from slipping.

In the event of the heel being excessively tender the parts can be so arranged that no appreciable pressure need be brought thereon 55 when the weight of the horse is brought upon the shoe. Moderate pressure of the heel on the connecting-bar even in the case of a tender heel is not, however, a serious objection, as the bar yields to such pressure. In fitting the 60 shoe to a healthy foot the frog will desirably be made to bear with some pressure upon the connecting-bar, whereby the pressure transmitted to the central part of said bar will cause the bar to adhere more firmly to the roadway, 65 and thus prevent the shoe from slipping.

The body of rubber occupying the rabbet

portion of the upper surface of the shoe, as well as the upper surface of the transverse bar B', will desirably be protected by a canvas or like covering. Said body of rubber 70 when the canvas is placed thereon will desirably extend flush with the extreme upper surface of the shoe, so that the rigid unyielding part of the shoe when fitted upon the foot may be placed at once against the hoof and secured 75 firmly thereto.

The body of the shoe will in practice be formed from steel between suitably-shaped dies by a forging process, and the rubber constituting the pad and that overlying the foot- 80 surface of the shoe will be molded on the shoe in a suitably-constructed mold, in a manner familiar to persons acquainted with this art and the rubber thereafter vulcanized.

From the foregoing it will be noted that at 85 the rear end of the shoe there are no metal parts to come into contact with the roadway or the foot of the horse, so that the heel of the foot is relieved from pressure such as would occur if the metal of the shoe were continued past 90 the connecting-bar at the levels of the tread of the shoe and the foot-surface thereof. In our construction the parts of the shoe which receive the first pressure when the foot is placed upon the ground—to wit, the rear ends of the 95 shoe—are yielding parts and relieve the horse of concussions and jars, while in a construction where the metal of the shoe is exposed to the extreme ends thereof said metal parts first strike the roadway and transmit practically 100 the entire jar or concussion to the horse. Moreover, in a shoe having a connecting-bar, as herein shown, and having metal parts which are exposed to the extreme end of the shoe the adhesion of the bar to the roadway 105 would be slight as compared with our construction.

We claim as our invention—

1. A horseshoe comprising a curved body provided on its under surface with calks, the 110 rear ends of said body extending in rear of the calks and being offset below the level of the body and above the level of the tread-surfaces of the calks.

2. A horseshoe comprising a curved body, 115 and inner and outer continuous calks, the rear ends of said body extending in rear of the calks and being offset below the level of the body and above the level of the tread-surface of the calks.

3. A horseshoe having a yielding body which envelops the rear ends of the shoe, the exposed metal part of the shoe terminating in advance of the part of the shoe which supports the heel of the animal, and said exposed metal part of the shoe being adapted 125 for contact with the roadway.

4. A horseshoe having the rear ends thereof connected by a bar of yielding material, said bar enveloping said rear ends of the shoe, the 130 exposed metal part of the shoe terminating a distance in advance of the part of the shoe

- which supports the heel of the animal, and said exposed metal part of the shoe being adapted for contact with the roadway.
5. A horseshoe comprising a curved body, provided on its under surface with calks, the rear ends of said body extending in rear of the calks and being offset below the level of the body and above the level of the tread-surfaces of the calks, and a pad attached to the under surface of said body and enveloping the rear offset ends thereof.
6. A horseshoe comprising a curved body provided with calks, a yielding bar connecting the rear ends of said body, the rear ends of said body being provided with projections which are offset above the tread of the shoe, and which are embedded in the connecting-bar.
7. A horseshoe provided with a yielding bar which extends between and connects the rear ends of said shoe, and in which the ends of the shoe are embedded, said bar being forwardly curved between its ends, and the ends of the shoe extending rearwardly past the concave curve of said bar.
8. A horseshoe provided with a yielding pad which extends around the under surface of the shoe, and an integral bar connecting the rear ends of said pad, in which bar the rear ends of the shoe are embedded, said bar being curved between its ends toward the toe of the shoe, and the ends of the shoe extending rearwardly past the concave curve of said bar.
- 35 9. A horseshoe comprising a curved body, inner and outer calks constructed to form between the same a channel, a yielding pad filling said channel, and an integral yielding bar connecting the rear ends of said pad, in which bar the ends of the shoe are embedded, said bar being curved between its ends toward the toe of the shoe, and the ends of the shoe extending rearwardly past the concave curve of said bar.
- 45 10. A horseshoe provided with a yielding bar which extends between and connects the rear ends of said shoe, and in which the ends of the shoe are embedded, said bar being forwardly curved between its ends and the ends of the shoe extending rearwardly past the concave curve of said bar, and the bar being made of greater depth than the depth of the shoe at the toe thereof.
- 55 11. A horseshoe having a yielding body which envelops the rear ends of the shoe, the exposed metal part of the shoe terminating in advance of the part of the shoe which supports the heel of the animal, and said exposed metal part of the shoe being adapted for contact with the roadway, said bar, at the rear of the shoe, being made of greater depth than the depth of the shoe at the toe thereof.
12. A horseshoe comprising a curved body, a yielding pad attached to the under surface of said body, and an integral yielding bar connecting the rear ends of said pad and enveloping the rear ends of the body of the shoe, said bar being made of greater depth than the depth of the shoe at the toe thereof.
13. A horseshoe comprising a curved body, inner and outer continuous calks constructed to form between the same a channel, a yielding pad filling said channel, and forwardly-facing oblique surfaces in said channel at the rear ends thereof which engage corresponding oblique surfaces on the pad.
14. A horseshoe comprising a curved body, inner and outer continuous calks constructed to form between the same a channel, one of said calks being corrugated, a yielding pad filling said channel, and forwardly-facing oblique surfaces in said channel at the rear ends thereof which engage corresponding oblique surfaces on the pad.
15. A horseshoe comprising a curved body, inner and outer calks constructed to form between the same a channel, a yielding pad filling said channel, and an integral yielding bar connecting the rear ends of said pad, said bar having wide tread and foot surfaces, and curved between its ends toward the toe of the shoe, the ends of the shoe being embedded in the material of the bar and said ends of the shoe extending rearwardly past the concave curve of the bar.
16. A horseshoe comprising a curved body, continuous calks constructed to form between the same a channel, a yielding pad filling said channel, an integral yielding bar connecting the rear ends of said pad, the body of said shoe being provided with offset extensions which are embedded in said bar, and said body and extensions being provided with openings through which extend integral bonds connecting the rubber on the upper and lower sides thereof.
17. A horseshoe comprising a curved body, inner and outer continuous calks constructed to form between the same a channel, a yielding pad filling said channel, an integral yielding bar connecting the rear ends of said pad, the rear ends of said body being provided with offset converging projections which extend beyond the calks and are embedded in the connecting-bars.

In testimony that we claim the foregoing as our invention we affix our signatures, in presence of two witnesses, this 18th day of February, A. D. 1901.
